J. M. FRANK

ELECTRIC HEATER

Filed Jan. 21, 1924

INVENTOR.

John M. Frank,
By Samuel N. Pond,
ATTORNEY.

UNITED STATES PATENT OFFICE.

JOHN M. FRANK, OF CHICAGO, ILLINOIS, ASSIGNOR TO ILG ELECTRIC VENTILATING COMPANY, OF CHICAGO, ILLINOIS, A CORPORATION OF LOUISIANA.

ELECTRIC HEATER.

Application filed January 21, 1924. Serial No. 637,436.

This invention relates to electric heating devices of the type commonly known as grid heaters and which, generally described, comprise a grid-like structure or a group of such structures bonded together and heated by the passage of a current of electricity through the resistance parts or elements of the grid or grids.

In designing my present heater I have had chiefly in mind its adaptability and utility for heating a current of air flowing through the grid. There are a number of situations where a heater of this character may be usefully employed. For instance, in a co-pending application for a heating and ventilating apparatus, Serial No. 682,163, filed December 22, 1923, I have disclosed the use of an electric heater for warming a current of air induced or propelled into a room by a fan; the air current being caused to travel across and through the electric heating element. Where a heater is used in this way, it is desirable that the heater itself shall be so designed as not only to possess as large a radiating capacity as possible, but also to offer the minimum resistance or obstruction to the flow of the air; and to provide a heater of such a design has been one of the objects of the present invention. Other more specific objects are, to provide a heater of very simple, rugged and economical construction; to provide a heater affording a large area of radiating surface in relation to its size and its capacity to readily permit the flow of air therethrough, to provide a heating grid having limbs which shall possess an oval or substantially stream-line form in cross-section in a direction transverse to the plane of the grid and having such limbs equipped with heat-radiating fins also so formed and arranged as to offer a minimum resistance to the flow of air; and to provide a heating grid of such a structure that duplicate units thereof may readily be assembled on a common support in such a manner that corresponding limbs of laterally adjacent grids will be relatively staggered or offset, so that the air flowing through the stack of grids thus assembled will have to follow a serpentine path, thereby picking up a maximum amount of heat during such flow.

Other objects and attendant advantages of the invention will be apparent to persons skilled in the art as the same becomes better understood by reference to the following de-

tailed description, taken in connection with the accompanying drawing in which I have illustrated one practical form of the invention, and wherein—

Fig. 1 is a side elevation of my improved electric heater grid, showing duplicate upper and lower sections for the sake of increased capacity, but either section alone embodying the broad principle of the invention;

Fig. 2 is a top plan view of a group or stack of grids such as is shown in Fig. 1 in assembled relation; and

Fig. 3 is an enlarged cross-section through one of the intermediate limbs of the grid.

Referring to the drawings, and first describing the unitary grid structure, this comprises parallel spaced bars 5 that constitute the side frame limbs of the grid, and an intermediate group of narrower parallel limbs 6 lying in the plane of the bars 5 and integrally connected to each other at their opposite ends by curved portions 6' of the same cross-section as the limbs 6. The greater cross-section of the side frame limbs 5 is to afford mechanical strength; and the outer limbs 6 are integrally joined to the limbs 5 by curved portions 5', thus forming a continuous zigzag structure. As shown in Fig. 2 and especially in the sectional view Fig. 3, the limbs of the grid are of generally oval or stream-line form in cross-section, with the major axis of the oval transverse and preferably normal to the plane of the grid. To increase the heating capacity of the grid the limbs thereof are equipped at spaced intervals with radial fins 7 on their adjacent sides, these fins being crescent shaped and widest at their central portions and gradually narrowing and merging into the body of the limb at the ends of the major axis of the latter. It will also be observed that the fins on adjacent limbs are relatively offset or staggered. When made in this form, and so arranged, the fins 7 substantially increase the heating surface and capacity while offering but very slight additional frictional resistance to the passage of the air.

On the free ends of the outer limbs 5 of the grid are formed apertured hubs 8; and where the grid is made double, that is, with like upper and lower relatively inverted sections, as shown in Fig. 1, the hubs 8 are made common to the corresponding limbs 5 of both sections, being located at the juncture of said limbs and serving to integrally connect them.

Where a heater is composed of a plurality of grids, these may be assembled side by side and connected by through bolts 9 extending through the several hubs 8, with suitable sleeve insulation 10 between the bolts and the hubs. 11 designate a pair of tie plates through which the bolts 9 also pass, and 12 are nuts on the projecting ends of the bolts 9 for bonding the structure together. The tie plates 11 may also serve in part as a means for supporting the grid on, or attaching it to, the structure it is designed to serve.

13 designate metallic washers, and 14 insulating washers, so disposed on the bolts 9 and between the hubs of the several grid sections as to insure a zigzag flow of the current from one grid to and through the succeeding grids of the series. For instance, in Fig. 2 I have shown the current entering by a circuit wire 15 to one of the metallic washers 13 at the left of the front of the grid, whence the current flows through the front grid thence crosses through the metallic washer 13 at the other side to the second grid, flowing back through the latter, thence through the second metallic washer at the left to and through the third grid, and thence through the metallic washer at the rear on the right hand side and out through the circuit line 16. Now, by reference to Fig. 2 it will be observed that the limbs 6 of each grid lie directly in front of or behind the spaces between the similar limbs of the next adjacent grid. By reason of this arrangement, in a multiple grid heater, a current of air flowing through the grid necessarily follows a more or less serpentine path, as shown by the arrows in Fig. 2, whereby it is caused to come into most intimate contact with each section of the heater thereby picking up the maximum amount of heat from the latter. This alternate or staggered arrangement is very simply and economically effected, from a manufacturing standpoint, by so building each grid that, while the several limbs 6 are equally spaced from each other, the outer limb 6 on one side is nearer to its adjacent supporting limb 5 than is the corresponding outer limb 6 on the opposite side to its adjacent supporting limb 5. The result is that the grids may all be made exactly alike; and, to obtain the staggered or offset grouping hereinabove described, it is necessary only to relatively sideways invert adjacent grids of the group. By reason of the described structure the frictional and other resistance offered to the passage of an air current through the heater is reduced to a minimum.

60 While I have described my invention as mainly designed for the heating of a current of air drawn or propelled therethrough, and

contemplate that such will be its principal application and use, yet I do not wish to be understood as limiting the invention to an electric heater for warming a current of air flowing therethrough, since the described structure of grid, and the multiple grouping or arrangement thereof herein shown, may manifestly be used to advantage in other situations and relations where an electric heater is desired or required.

I claim—

1. An electric heater grid, including a plurality of spaced parallel limbs located in a common plane and provided with radial fins on their adjacent sides, the fins on adjacent limbs being relatively offset or staggered. 75

2. An electric grid, including a plurality of spaced parallel limbs located in a common plane and of a generally oval form in cross-section with the major axis of the oval transverse to said plane; said limbs being provided with radial fins of crescent shape 85 on their adjacent sides. 80

3. An electric grid, including a plurality of spaced parallel limbs located in a common plane and of stream-line form in cross-section with their major transverse axes normal to said plane; said limbs being provided with radial fins of crescent shape on their adjacent sides, and the fins on adjacent limbs being relatively offset or staggered. 90

4. An electric heater, comprising a plurality of grids each formed with spaced parallel limbs disposed in a common plane, means for uniting said grids in side-by-side relation, the limbs of adjacent grids, when the latter are united, being relatively offset laterally, and means for passing current through said grids in succession. 95

5. An electric heater, consisting of a group of duplicate grids disposed side by side and each comprising a pair of spaced side frame limbs formed with apertured hubs and a group of intermediate parallel limbs located between and in the plane of said side frame limbs and lengthwise continuous with the latter and with each other, the outermost limbs of said intermediate group being differentially spaced from their adjacent side frame limbs and adjacent grids being relatively inverted sidewise whereby their intermediate limbs are relatively offset or staggered laterally, insulated tie-bolts passed through the hubs of the grids and bonding the latter together, and alternately arranged conducting and insulating washers on said tie-bolts between adjacent hubs, whereby current is passed through said grids in succession from one side of the group to the other. 105 110 115 120
